UNITED STATES PATENT OFFICE.

LOUIS STEINBERGER, OF BROOKLYN, NEW YORK.

DESIGN FOR A VARIOMETER.

Application filed November 8, 1922. Serial No. 4,240. Term of patent 14 years.

To all whom it may concern:

Be it known that I, LOUIS STEINBERGER, a citizen of the United States, and a resident of the borough of Brooklyn, county of Kings, city and State of New York, have invented a new, original, and ornamental Design for Variometers, of which the following is a specification.

The design is illustrated in the accompanying drawing, in which,

Fig. 1 is a perspective view of the variometer,

Fig. 2 is a top plan view of the variometer.

I claim:

The ornamental design for a variometer, as shown.

In witness whereof I have hereunto set my hand at the city, county and State of New York, this 2d day of November, 1922.

LOUIS STEINBERGER.
